PETER C. SMITH, OF PROVIDENCE, RHODE ISLAND, ASSIGNOR TO HIMSELF, EZRA S. DODGE, AND LOUIS A. KOTZOW, OF THE SAME PLACE.

Letters Patent No. 88,338, dated March 30, 1869.

SAFETY-TOGGLE FOR WATCH-CHAINS.

The Schedule referred to in these Letters Patent and making part of the same.

To all whom it may concern:

Be it known that I, PETER C. SMITH, of the city and county of Providence, and State of Rhode Island, have invented a new and useful Safety-Toggle for Vest-Chains and other similar purposes.

To enable persons skilled in the art to make and use my invention, I do hereby declare that the following specification, taken in connection with the drawings furnished and forming a part of the same, is a true and clear description thereof.

Figure 1 represents one of my toggles in perspective, with portion of watch-chain attached.

A represents a face-plate, more or less ornamented, and of any desired form, furnished with a hook, or ring, to which the chain is permanently attached.

B B are flat standards, soldered to the back of the face-plate, connecting it with the bar of the toggle by means of the barrel.

C is the barrel within which the bar proper operates.

D is a sliding bolt, or bar proper, near one end of which is a shoulder bearing against one end of the barrel C. The other end is of the same size as the interior of the barrel. A portion of the middle of the bar D is much smaller than at either end, around which is coiled a spiral spring, so set as to bear against a shoulder within the barrel C, and by pressure against a corresponding shoulder on the bar, forces it out, so that each end of the bar projects equally from the barrel.

Figure 2 represents, in section, one of my toggles, showing the interior of the barrel C, and the spiral spring, before referred to.

The operation of the toggle is as follows:

By pressing upon the proper end of the bar D, it is forced through the barrel C, and while in that position, is readily inserted into the button-hole of a vest or other suitable aperture. Upon being released from pressure, the bar springs out, and the toggle is securely attached to the vest, requiring the same particular ma-

nipulation to release it that was requisite for its insertion.

I am well aware that shirt-studs, and perhaps sleeve-buttons, have been made before, possessing a barrel, or round standard, a bar, and a spiral spring, operating in a similar manner to the bar of my toggle. Such fastenings have a great value, but have hitherto been adapted only to eyelet-holes, and would not serve for use with the ordinary button-hole.

I wish it distinctly understood, therefore, that I make no claim to the use of the bar, the barrel, and the spring, in the formation of a safety-fastening.

My invention relates to a distinctive feature, novel to the trade, in the manufacture of watch-chains, resulting in a new article in the line of toggles, hitherto made of a straight bar, of a single piece of metal, inserted by the end, with a portion of the chain, through the button-hole, and then adjusted by the withdrawal of the chain.

The double standards B occupy an important position as points in my invention, as, by their construction and position, the toggle is kept (while being worn) firmly in the button-hole, and does not sag down, or wear the hole by motion, as in the case of the ordinary toggle. These standards can be formed in one piece, sufficiently broad to answer the purpose, although I prefer the double, as being lighter and neater.

Having thus described my invention,

I claim as new, and desire to secure by Letters Patent—

The safety-toggle, consisting of the face-plate A, the standards B, the barrel C, the bar D, and spring E, constructed and operating substantially as herein described, for the purposes specified.

PETER C. SMITH.
